UNITED STATES PATENT OFFICE.

NILS D. LEVIN, OF COLUMBUS, OHIO, ASSIGNOR TO THE JEFFREY MANUFACTURING COMPANY, A CORPORATION OF OHIO.

MINING-MACHINE AND TRUCK.

1,170,763.

Specification of Letters Patent.

Patented Feb. 8, 1916.

Application filed April 25, 1910, Serial No. 557,432. Renewed June 18, 1914. Serial No. 845,975.

To all whom it may concern:

Be it known that I, NILS D. LEVIN, a citizen of the United States, residing at Columbus, in the county of Franklin and State 5 of Ohio, have invented certain new and useful Improvements in Mining-Machines and Trucks, of which the following is a specification, reference being had therein to the accompanying drawing.

10 This invention relates to trucks, and has as its object to provide a truck onto which and from which a mining machine or other body can be readily loaded or unloaded, and which can be self propelled by the mining 15 machine motor.

Figure 1 of the drawings is a plan view of a truck embodying my invention. Fig. 2 is a side elevation of the same, a mining machine being shown thereon. Fig. 3 is a side 20 elevation of the truck with the front end depressed and in position for unloading or loading a mining machine, the mining machine being shown in this figure also. Fig. 4 is a vertical section of the clutch mechanism 25 on the truck by means of which the truck gearing is connected to the power devices of the mining machine. Figs. 5 to 12 inclusive are detail views of some of the parts of the said clutch mechanism.

30 It has been customary in using trucks of this kind to depress one end of the truck and consequently to raise the axle and wheels at the opposite end of the truck from the ground when it has been desired to put the 35 truck in position for loading or unloading a mining machine. When the truck is thus tilted on its front axle as a fulcrum, the rear end is raised sufficiently high to occasion serious difficulty in rooms where the 40 coal is found in very thin veins, the rear end of the truck or the mechanism carried by the rear end frequently striking the roof of the room. A truck built in accordance 45 with my invention is provided with a front supporting construction of such a type that the forward end of the truck may be lowered with respect to the front axle and again elevated to position after the mining machine has been moved into place upon the 50 truck.

The frame of the truck comprises the side rails 1, 1 and cross bars 2, 4 and 7. To the side bars 1 are secured bearing boxes 9 for the axles 10 and 11, upon which are mounted

the track wheels 12, 12 and 13, 13. The 55 wheels 13 are not keyed directly to the forward axle 10 but are rotatably mounted upon the short shafts 14 respectively, which are secured at their inner ends to the crank arms 15. These crank arms are keyed to the 60 ends of the axle 10, being disposed in the same plane through the axis of the axle 10. This construction provides, in effect, an axle bent at its two ends, and the wheels 13 are thus mounted eccentrically with respect 65 to the axle 10.

When the crank arms 15 are in the position shown in Fig. 2 the axle 10 is in a plane somewhat above the horizontal plane of the axle shafts 14 and the truck frame is in its 70 normal raised position; by swinging the axle 10 downward around the axis of the shafts 14 to a position somewhat below the plane of the shafts 14, the frame of the truck is lowered to the position shown in Fig. 3 of 75 the drawings, in which position the mining machine can readily be drawn onto or off of said frame. In swinging the front axle 10 as just described, it will be observed that the distance between the shafts 14 and 80 the axle 11 is not greatly changed.

The cranks 15 have formed integral therewith upwardly extending arms 16 which are adapted to be engaged and moved by rollers 17 which are appropriately mounted one 85 upon each side of the mining machine 18. As the mining machine is moved onto the truck in any usual or preferred way, the rollers 17 engage the arms 16 while moving from the position shown in Fig. 3 of the 90 drawings. As the mining machine advances farther along the rails 1, the arms 16 are moved angularly about the pins 14, and the axle 10, which is supported at its ends in the crank arms 15, is elevated carrying with it 95 the front end of the truck, which is thus lifted into the same horizontal plane with the rear end of the truck. It is only when the mining machine is moved from the position shown in Fig. 2 of the drawings, that 100 the arms 16 which are held in their vertical position by the mining machine are allowed to assume their inclined position, as shown in Fig. 3, and the forward end of the truck is then automatically lowered until the machine can be readily withdrawn therefrom.

When the mining machine is in its proper position upon the truck for transportation

about the mine, the clutch element 19 at the lower end of the main power shaft 20 of the mining machine is in mating position over the clutch element 22 mounted upon the truck by being secured to the cross bar 4 and the longitudinal bar 21 of the truck frame. It is by this means that the power of the mining machine motor 23 is delivered to the wheels of the truck. When the mining machine is in normal position upon the truck, the truck is propelled along the mine tracks by the mining machine motor.

Difficulty has been heretofore experienced in securing a proper connection of the power transmitting mechanism on the mining machine with the power transmitting mechanism on the truck, and this difficulty is especially great when the connection is a shaft coupling between two vertically arranged shafts, one upon the mining machine and one upon the truck. To overcome this difficulty I have devised the following form of clutch or coupling.

Upon the lower end of the power shaft 25 of the mining machine is secured the disk 19 radially notched at 35, 35. This shaft 20 is capable of being raised or lowered carrying with it the disk or clutch element 19. When the shaft is in its lower position, 30 the clutch element 19 mates with the clutch element 22. When the shaft is not in its lowermost position the clutch is disconnected.

The stud 24 is secured in fixed vertical position to the frame plate 25, which latter is appropriately secured to the frame bars 4 and 21 of the truck. The sleeve 26 is journaled upon this stud and upon it is keyed or otherwise rigidly secured the 40 sprocket wheel 27. The sleeve 26 has an upper disk-like integral extension 28, which is formed with two upwardly extending driving keys 29 on its upper side. The driving keys 29 fit snugly within and slidably engage the groove 30 in the under side of the intermediate plate 31. This plate has formed in its upper side another groove 32 arranged at right angles to the groove 30. The sum of the depth of these two grooves 50 is at least equal to the thickness of the intermediate plate 31 in which they are formed, with the result that the plate is provided at its center with a square aperture 33 extending completely through it. The groove 32 slidably engages driving keys 34 formed on the under side of the clutch element 22. This element 22 is formed with the teeth 22^a, which engage with the notches 35, 35. The inner end wall of these notches and 60 also of the teeth 22^a which mate therewith are inclined downward and radially inward. This inclination of the inner walls of the notches and teeth causes the two clutch elements to be properly connected even though the upper element may be laterally displaced

in any direction with respect to the lower element. Such displacement is quite apt to be the case, since it is difficult to cause the mining machine to assume such a position than the two clutch elements are exactly 70 alined with each other. When the clutch elements are thus displaced, the inclination of the inner ends of the notches and teeth causes the clutch element 22 to be moved into alinement with the clutch element 19, 75 as the latter is lowered to its mating position. The clutch element 22 is readily movable laterally with respect to the stud 24, because the intermediate plate 31 has sliding engagement in two directions perpendicular 80 to each other with the clutch element 22 and the sleeve 26 respectively. When the clutch is in operation under such circumstances, clutch element 22 will rotate about the same axis as will the clutch element 19; the sleeve 85 26 will rotate about another axis displaced therefrom; and the intermediate plate 31 will have an eccentric motion both with respect to the axis of rotation of the clutch element 22 and with respect to the axis of 90 rotation of the sleeve 26 and will transmit power from one to the other.

To prevent the clutch element 22 from becoming sufficiently displaced laterally to be entirely disconnected from the parts upon 95 which it rests, and likewise to prevent a similar displacement of the plate 31 from a position upon the sleeve 26, the block 36 is placed in the aperture 33, which it snugly fits. Should the parts become displaced to 100 an excessive amount, the plug will engage the inner ends of the driving keys 29 in one direction of movement and the inner ends of the driving keys 34 in the other direction of movement and will prevent any further 105 horizontal displacement.

At the forward end of the truck, a vertical shaft 37 is mounted. This shaft is journaled within the box-like casing 38 and upon its lower end, which projects below the casing, the sprocket wheel 39 is keyed. The sprocket chain 40 connects the sprocket wheels 39 and 27. Within the casing 38 reversing power transmitting mechanism is contained, which connects the vertical shaft 110 37 to the horizontal shaft 41. By means of this reversing mechanism, the shaft 41 can be driven in either direction of rotation by the shaft 37 which preferably always rotates in the same direction. The shaft 41 115 projects horizontally through the end wall of the casing 38 and is provided with the sprocket wheel 42 which is connected to another sprocket wheel 43 on the axle 11 by means of the chain 44. Through this train 120 of gearing the mining machine motor, while rotating in the same direction, is utilized to drive the wheels 12 and to propel the truck in either direction. To secure additional 125 tractive effort, the axle 11 is connected to 130

each of the wheels 13 by means of the sprocket chains 45 engaging at the rear end the sprocket wheels 46 on the axle 11 and at the forward end sprocket wheels 47 engaging with the wheels 13. I have already pointed out that in adjusting the axle 10 up and down, the distance between the wheel shafts 14 and the axle 11 is not greatly altered, and for this reason it is not necessary to provide an undue amount of slack in the chains 45.

A reeling mechanism 48 is provided at the rear end of the truck to wind and unwind a conductor cable by which current is supplied from a stationary conductor to the mining machine motor, the reel being driven by the shaft 41, the rope wheel 49 thereon, the rope 50 and the rope wheel 51 on the reel shaft. The reel is reversed in direction of rotation when the direction of movement of the truck is reversed, since the shaft 41 drives both the reel and the truck. When the truck is moving toward the point at which the cable is secured to the stationary conductor, the reel winds the cable and prevents the formation of slack therein. When the truck is moving in the other direction the reel unwinds the cable and lays it along the track. In this manner, current is supplied to the mining machine motor without the use of trolley mechanism or other contact devices engaging an extended stationary conductor.

The operation of a truck constructed in accordance with my invention is apparent and its many advantages are evident. The truck is automatically raised and lowered at the proper times when the mining machine is being loaded or unloaded therefrom. The truck wheels are automatically connected or disconnected from the mining machine motor when the mining machine is moved into or away from its normal position upon the truck. The direction of movement of the truck can be reversed by means of the wheel 52, which operates the reversing clutch in the casing 38, without changing the direction of current from the motor 23. It is a great advantage not to have to reverse the direction of rotation of the mining machine motor, if possible. The reversing clutch also automatically reverses the direction of rotation of the reel 48, and the conductor cable 53 is automatically maintained taut without slack and without excessive tension.

I do not herein claim the combination of the truck with the cable reeling mechanism, as this construction is covered by my co-pending application for mining machines and trucks, Serial No. 579,798, filed August 31, 1910; and I do not herein claim the specific form of cable reeling mechanism shown, as a mechanism of this general character is covered by my co-pending application, for cab winding mechanism, Serial

No. 664,037, filed December 5, 1911, as a division of my aforesaid co-pending application, Serial No. 579,798.

The mining machine which is diagrammatically shown in the drawings is not here 70 specifically claimed, it being made the subject-matter of another application for mining machines, Serial No. 727,280, filed October 22, 1912.

What I claim is:

1. The combination of a wheeled truck, a mining machine having a clutch element arranged with its axis perpendicular to the longitudinal lines of the machine, a mating clutch element on the truck arranged with 80 its axis perpendicular to the longitudinal lines of the truck and mounted so as to be movable through a limited area in a plane perpendicular to its axis, and power transmitting gearing connecting the movable 85 clutch element with the truck wheels.

2. The combination of a truck body, flanged track wheels, and a clutch element adapted to mate with another clutch element on a mining machine on the truck, said 90 clutch element being arranged with its axis vertical, a power transmitting shaft on the truck, a shaft coupling between the shaft and clutch element permitting the latter to rotate in engagement with the mining machine clutch element at any position within a 95 limited area in a plane perpendicular to its axis, and power transmitting gearing between the shaft and truck wheels.

3. The combination of a truck frame 100 adapted to receive and carry a mining machine thereon, wheels supporting said frame and a train of gearing on the truck frame connected to the truck wheels and comprising coupling devices adapted to connect with 105 power devices on said mining machine when it is in position upon the truck frame and a manually operable reversing mechanism, whereby the truck can be propelled in either direction by the power devices on the min- 110 ing machine.

4. The combination of a truck frame, wheels on the truck, a train of power transmitting gearing on the truck adapted to be connected at one end with power mechanism on the body carried by the truck and connected at the other end to the truck wheels, manually controllable reversing mechanism in the said train, a reel mounted on the truck, a flexible conductor wound on 120 the reel, and power transmitting gearing connecting the reel to an element in the said train located operably between the reversing mechanism and the wheels.

5. The combination of a truck frame, a 125 pair of axles mounted thereon, a pair of supporting wheels mounted on the rear axle, a pair of crank arms on the ends of the front axle, supporting wheels rotatably mounted on the outer ends of the crank arms, and 130

levers rigidly secured to the crank arms and arranged to be engaged by the body carried by the truck as it is moved onto the truck.

- 5 6. The combination of a truck frame, a pair of axles mounted thereon, a pair of supporting wheels mounted on the rear axle, a pair of crank arms on the ends of the front axle, supporting wheels rotatably mounted on the ends of said crank arms, driving connections between the front axle wheels and the rear axle wheels comprising a sprocket chain, and means for swinging the front axle from a position somewhat below a horizontal plane through the axis of the front wheels to a position somewhat above said plane, the proportions and arrangements of parts being such that the frame is in its inclined loading and unloading position when the axle is in the said position below the plane of the axis of the wheels, and in its normal horizontal position when the axle is in the said position above the said plane.
- 10 7. The combination of a truck frame, a pair of axles mounted thereon, a pair of supporting wheels mounted on the rear axle, a pair of crank arms on the ends of the front axle and extending approximately horizontally therefrom, supporting wheels rotatably mounted on the outer ends of the crank arms, and two upwardly extending levers rigidly connected to the crank arms respectively at their wheel ends and making an angle of approximately ninety degrees therewith and adapted to be engaged by parts on the article transported as it moves into position on the truck and to be moved thereby so as to angle the crank arms and 15 elevate the front axle sufficiently to raise the truck frame from an inclined position to a horizontal position.
- 15 8. The combination of a truck frame, a pair of axles mounted thereon, a pair of supporting wheels mounted on the rear axle, a pair of crank arms mounted on the ends of the front axle, supporting wheels rotatably mounted on the outer ends of the crank arms, and two upwardly extending 20 levers rigidly connected to the crank arms

respectively and adapted to be engaged by parts on the article transported as it moves into position on the truck and to be moved thereby so as to angle the crank arms and elevate the front axle sufficiently to raise the truck frame from an inclined position to a horizontal position.

9. The combination of a truck, comprising a frame and supporting wheels therefor, a train of gearing on the truck for driving the supporting wheels, and a mining machine having power driven mechanism, the power driven mechanism of the mining machine and the gearing of the truck comprising respectively rotatable power transmitting members adapted to be brought into substantial alinement and connecting mechanism including clutch elements adapted to co-act and transmit power from the said rotatable member on the mining machine to the said rotatable member on the truck when the rotatable members are, within certain limits, out of alinement with each other.

10. The combination of a truck, comprising a frame and supporting wheels therefor, a train of gearing on the truck for driving the supporting wheels, and a mining machine having power driven mechanism, the power driven mechanism of the mining machine and the gearing of the truck comprising respectively rotatable power transmitting members adapted to be brought into substantial alinement and connecting mechanism including clutch elements adapted to co-act and transmit power from the said rotatable member on the mining machine to the said rotatable member on the truck when the rotatable members are, within certain limits, out of alinement with each other, the said clutch elements being provided with beveled surfaces adapted to engage each other to cause the automatic alinement of the elements.

In testimony whereof I affix my signature, in presence of two witnesses.

NILS D. LEVIN.
